 2 SHEETS—SHEET 2.

UNITED STATES PATENT OFFICE.

EDWARD B. ELICOTT, OF CHICAGO, ILLINOIS, ASSIGNOR TO GENERAL ELECTRIC COMPANY, A CORPORATION OF NEW YORK.

CUT-OUT AND FUSE MECHANISM.

1,087,357.

Specification of Letters Patent.

Patented Feb. 17, 1914.

Application filed January 4, 1909, Serial No. 470,631. Renewed December 3, 1910. Serial No. 595,489.

To all whom it may concern:

Be it known that I, EDWARD B. ELICOTT, a citizen of the United States, residing at Chicago, in the county of Cook and State of Illinois, have invented a certain new and useful Improvement in Cut-Out and Fuse Mechanism, of which the following is a full, clear, concise, and exact description, reference being had to the accompanying drawings forming a part of this specification.

My invention relates to cut-out and fuse mechanism, particularly for high tension systems, its object being to provide improved construction and more safe and efficient operation.

My invention is embodied in the structure shown in the accompanying drawings, in which:

Figure 1 being a side elevation view of my improved apparatus; Fig. 2 being an end elevation thereof; Fig. 3 showing the fuse holder; Fig. 4 being a sectional view on plane 4-4 of Fig. 1; Fig. 5 being a view of the lower end of Fig. 4; and Fig. 6 being a top view of the fuse holder handle.

The supporting structure for my improved apparatus is in the form of a frame, preferably of malleable iron, and comprising a horizontal part 1, and the vertical post 2 extending from one end of the part 1. Extending downwardly at right angles with the part 1 is the plate 3, strengthened by webs 4. Between the plate 3 and the post 2 is the downward extension 5 parallel with the plate 3 and forming therewith a pocket for receiving a cross-arm, as 2, to which the supporting frame can be secured by means of bolts passing through openings 6 and edge slots 7 through the plate 3. The post 2 has threads 8 at its end for receiving a threaded body 9 of an insulator 10, preferably of glass or porcelain, this insulator having a petticoat 11. Fitting over and secured to the body 9 of the insulator is a metallic cap 12 of conductive material such as brass or copper, to which may be connected one terminal of a circuit by means of lugs 13 and screws 14. Secured to this cap and extending upwardly therefrom are two parallel plates or jaw members 15 and 16, between which is pivoted one end of a switch blade 17 by means of pivot screw 18.

At the left end of the frame 1 is located the fuse frame, substantially tubular in general design, and at right angles to the frame

1. The construction of this fuse frame is best shown in Fig. 4. The main support for the fuse frame is in the form of a tube 19 having internal threads at both ends, as shown. Engaging at the top of this tube is a terminal casting 20, whose cylindrical body part 21 is threaded to fit the internal threads of the upper end of the tube 19, a horizontal flange 22 on said casting engaging over the top of said tube. Also extending upward from the head of the casting are two parallel jaw members 23, 24, preferably of copper, these jaw members receiving between them the other end of the switch blade 17, the bolt 25 passing through the jaw members enabling adjustment thereof. A flange 26 also extends downwardly from casting 20, said flange being of less diameter than the threaded part 21 and forming the pocket 27. A plurality of V-shaped contact sleeves 28 have their outer limbs 29 secured to the outer face of the flange 26, while the inner limbs 30 project into the pocket 27 to form a conical spring contact pocket. At the lower end of the tube 19 is a sleeve 31 so having a threaded part 32 for engaging the inner threads at the lower end of the tube 19, and having the flange 33 at its lower end for engaging over the end of tube 19. The flange 33 is provided with a plurality of threaded openings 34, so that terminal lugs 35 can be secured by means of bolts 36. As will be shown, the terminal castings 20 and 31 are adapted to receive the terminals of a fuse holder, the fuse within the holder and the switch blade serving to electrically connect the terminal frame 12 and the terminal frame 31. In practice, the main wire connects with the terminal 12 and supplies current through the switch blade and fuse to any number of circuits connected with the terminal frame 31.

Lining the tube 19 and extending approximately between the terminal frames 20 and 31 is a tube 37, preferably of fire-proof material such as asbestos. Surrounding the upper half of sleeve 31 is the insulator 38, and surrounding the lower half of said tube is the insulator 39, both insulators being preferably of glass or porcelain and having each any desired number of petticoats 40. Between the insulator 38 and the tube 19 is a bushing 41 of suitable insulating material or compound, and between the lower insulator and the tube there is a 110

bushing 42 of suitable insulating material or compound. Between the upper and lower insulators is clamped the frame 1. This frame at its left end has the circular opening 43 and the annular pocket 44 surrounding said opening. The upper end 45 of the lower bushing 42 is flanged and fits in the opening 43, while between the lower end of the upper insulator and bushing is interposed some cushioning and insulating material as washers 46 of weatherproof press-board or other material, these washers fitting into the pocket 44. Upon assembly of the apparatus the contact frame 31 is screwed into the lower end of the tube 19 and the lower insulator and its bushing slipped over to rest against the flange 33. The upper part of the tube 19 is then slipped through the opening 43 in frame 1 and the washers 46 supplied, and then the upper insulator and its bushing slipped over the tube, whereupon the upper contact frame 20 is screwed into the upper end of tube 19, its flange 22 engaging the top of insulator 38, the insulators being drawn toward each other to clamp between them the frame 1, the fuse holder supporting frame being, therefore, securely held in vertical position. To prevent breaking or cracking of the insulators, washer material 47 may be applied between the flanges 22, 33 and the outer ends of the respective insulators. The arrangement described forms a very rigid construction, and the contact frames are thoroughly and lastingly insulated from each other and from the supporting frame 1.

The fuse holder is shown complete in Fig. 3 and in section in Fig. 4. This holder comprises a tube 48 of insulating material such as fiber, said tube being threaded at both ends to receive at its upper end a terminal head 49 and at its lower end a terminal frame 50. The terminal head 49 is tubular, its upper end 51 being conical and having interior threads 52 for receiving a screw 53, whose head forms a continuation of the conical part. This screw has the bore 54, from which a passageway 55 extends to the annular groove 56. The lower contact frame 50 comprises the upward extension 57 receiving the threaded lower end of the tube 48. Connecting the interior of the tube 48 with the exterior of tubular extension 57 is a passageway 58, adjacent to which a terminal screw 59 threads into the extension 57. A fuse wire 60 passes through the tube 48, its lower end extending through passageway 58 and clamped under the head of screw 59 to be in electrical contact with the lower contact frame 50. The upper end of the fuse wire extends through passageway 55 and through the groove 56 to be clamped into firm electrical engagement with the contact head 51 when the screw 53 is drawn tight. A set screw 61 can be provided for

locking the contact head 49 to the tube 48, and a set screw 62 can be provided for locking the threaded engagement of the contact frame 50 with the tube. The body part 63 of the lower frame 50 has greater diameter than the extension 57 so that it fits easily in contact sleeve 31 of the fuse holder frame. As best shown in Fig. 3, this body part is surrounded by a groove 64, to which there is the entrance slot 65. Secured to and extending radially inward from the contact sleeve 31 is a pin 66, this pin being adapted to form bayonet coupling arrangement with the entrance 65 and groove 64. Extending downwardly from the interior of said body part and in register with the tubular extension 57 and fuse holder tube 48 extends the tubular arm 68, whose lower end is bifurcated to form the slot 69. This slot is adapted to receive the pin 70 extending across the end sleeve 71 on the handle 72. When it is desired to insert a fuse holder into the fuse holder supporting frame, the handle 72 is applied to the lower end of the fuse holder, the lower end of tubular extension 68 passing into the sleeve 71 and the pin 70 entering the slot 69. The fuse holder is now inserted through the contact sleeve 31, the conical end of the contact head 49 engaging the contact pocket 30 surrounding the lower end of the contact casting 20. The holder upon insertion is primarily in position so that the entrance 65 will receive the pin 66, and the upward movement of the fuse holder is limited by the engagement of this pin with the lower wall of the groove 64. The handle is then turned either to the left or to the right so that the locking groove 64 will receive the pin and the fuse holder will be locked in position, and the handle can then readily be pulled from the tube extension 68.

The conical end of the contact pocket 30 is such that the springs will have a tendency to expel the fuse holder head 57, and this spring tension is transmitted to the bayonet coupling members and the fuse holder will be held securely in locked position without danger of becoming jarred and vibrated to the unlocked position. If the fuse should blow, the fuse holder can readily be removed by applying the handle to the lower part thereof, and then first rotating to unlocking position and then drawing out the holder. If, as a result, the fuse tube is broken, there will be no danger of the contact head 57 being held by the contact sleeves upon withdrawal of the lower part of the holder supporting frame, but the construction of these springs as above described will cause expulsion of the contact head, which will then drop from the holder supporting frame after the lower part of the fuse holder has been withdrawn and the asbestos inner tube or lining 37 protects the fiber against the

sparks formed upon rupture of the fuse. Gases generated within the fuse holder 48 can escape directly to the atmosphere through the tubular extension 68, or can escape through the screw 53 and passageway 58 into the fuse holder supporting frame and from there to the exterior through passageways extending through the body part 63 of the fuse holder contact frame 50. With my arrangement as described, the fuse holder can very quickly and safely be inserted or withdrawn from the fuse holder supporting frame. The construction is such that when the entire structure is mounted on a support such as a cross-arm, the structure will be perfectly balanced. By means of the additional contact 12 and the switch blade 17 the structure can be used as a cut-out, which makes it very convenient for testing purposes or in case of trouble on a line. This additional contact and switch mechanism can, however, be omitted and a contact provided in place of the jaw members 23, 24, so that the line terminals can be connected directly with the contact frames 20 and 31. The fuse holder supporting structure is weather proof and its insulating qualities are practically permanent. It is also fireproof and being of strong construction is proof against violent blowing of fuses. After a blow-out, therefore, repairs will not have to be made to the supporting structure, and at most a new fuse holder tube may be substituted for the one destroyed upon blowing of the fuse. The construction is also such as to discourage mischievous persons, as contact with extension 68 would most likely result in a severe shock. By use of the carefully insulated handle, however, connection with the fuse holder can be safely made.

It is understood, of course, that modifications in the construction and arrangements given are possible which will still be included in my invention. I do not, therefore, limit myself to the precise construction and arrangement which I have shown and described, but desire to secure the following claims by Letters Patent:

50 1. In fuse mechanism, the combination of suitable supporting structure, a contact frame secured at one end of said structure, a plurality of contact springs secured to said contact frame and arranged to form a conical contact socket, a companion contact frame secured at the other end of the supporting structure and having a passageway extending therethrough and toward the contact socket, a fuse holder having a tapered contact head at one end and a contact plug at the other, said fuse holder being adapted for insertion through said passageway to carry its contact head into engagement with the contact springs forming the contact socket and to carry its contact plug into

electrical engagement with the companion contact frame, said contact springs tending to expel the fuse holder contact head, and locking means associated with the companion contact frame and the fuse holder 70 contact plug for locking said fuse holder in electrical association with the contact frames.

2. In fuse mechanism, the combination of a supporting structure, contact springs secured at one end of said structure and forming a contact socket, a contact sleeve secured at the other end of the supporting structure, a fuse holder having a tapered contact head at one end and a contact plug at the other, said fuse holder being adapted for 75 insertion through said sleeve contact to carry its head into said spring contact socket and its plug into electrical engagement with said sleeve contact, said contact springs tending to expel said contact head, and locking 80 means for locking the fuse holder in position to hold the contact head in firm electrical engagement in said contact socket formed by said contact springs.

3. In fuse mechanism, the combination of 90 a supporting structure, contact springs secured at one end of said structure and forming a contact socket, a contact sleeve secured at the other end of the supporting structure, a fuse holder having a tapered contact head 95 at one end and a contact plug at the other, said fuse holder being adapted for insertion through said sleeve to carry its head into said spring contact socket and its plug into electrical engagement with said sleeve contact, said contact springs tending to expel 100 said contact head, and locking means for locking together the fuse holder plug and the sleeve contact, whereby said fuse holder is maintained to form electrical engagement 105 with said contact springs.

4. In fuse and cut-out mechanism, the combination of a metallic horizontal supporting frame having an integral vertical extension at one end, an insulating member 110 secured to the top of said extension, a terminal frame secured to the top of said insulating member, a switch blade pivoted to said terminal frame, a tubular supporting structure secured at an intermediate part to 115 the other end of said metallic frame and extending parallel with said extension, a contact frame at the upper end of said tubular supporting structure having contact jaws for receiving the free end of said switch 120 blade, a second contact on said tubular supporting structure, and a fuse holder having contacts for engaging said contact frame and said second contact.

5. In fuse and cut-out mechanism, the 125 combination of a metallic horizontal supporting frame having an integral vertical extension at one end, an insulating member secured to the top of said extension, a terminal frame secured on top of said insulator, 130

a switch blade pivoted to said terminal frame, a tubular supporting structure secured at an intermediate part to the other end of said frame and extending parallel with said extension, a contact frame secured to the end of said tubular supporting structure and having contact jaw members for receiving the free end of said switch blade, a terminal frame secured to the lower end 5 of said supporting structure and having a cylindrical passageway communicating and alining with the interior of said tubular structure, a fuse holder adapted for insertion through said passageway and into the 10 tubular structure, and a contact head and contact plug for said fuse holder adapted for engagement respectively with the contact frame and the cylindrical wall of the terminal frame at the ends of said tubular 15 support.

6. In fuse mechanism, the combination of a tubular supporting structure of insulating material, a contact frame secured to and extending into the upper end of said supporting structure, a flange extending from said contact frame beyond the supporting structure, a contact frame secured to and extending into the lower end of said tubular structure and having a passageway communicating and alining with the interior of the tubular structure, a flange extending from the lower contact frame and beyond the tubular structure, an upper insulating member surrounding the tubular structure, an insulating member surrounding the lower part of the tubular structure, and a supporting frame engaging the tubular structure between the adjacent ends of the insulating members, said flanges engaging the other 30 ends of the insulating members and causing said insulating members to clamp the supporting frame.

7. In fuse mechanism, the combination of a tubular supporting structure, a contact frame having threaded engagement with the upper end of said structure and having a flange extending laterally beyond the tubular structure, a contact frame having screw threaded engagement with the lower end of 35 said tubular structure and having a flange extending laterally beyond said tubular structure, said lower contact frame having a passageway alining with the bore of the

tubular structure, a supporting frame engaging at an intermediate point with the tubular structure, an insulating member surrounding the tubular structure between the supporting frame and the flange of the upper contact frame, an insulating member surrounding the tubular structure between the supporting frame and the flange of the lower contact frame, said insulating members being moved together upon threading engagement of the contact frames with the tubular structure whereby said supporting frame is clamped between the insulating members and the tubular structure thereby supported from said supporting frame, and a fuse holder adapted for insertion into the tubular structure through the passageway of the lower contact frame, said fuse holder having contact terminals for engaging the upper and lower contact frames.

8. In fuse mechanism, the combination of a tube of insulating material, a terminal frame having threaded engagement with one end of said tube and having lateral extensions, a terminal frame having threaded engagement with the lower end of said tube and having lateral extensions, there being a passageway through said lower terminal frame alining with the tube, a protecting member surrounding the upper part of the tube and engaging the lateral extensions of the upper terminal frame, a protecting member surrounding the lower part of the tube and engaging the lateral extensions of the lower tubular frame, a supporting frame clamped between the inner ends of the protecting members by the engagement of said flanges with the outer ends of said protecting members when the terminal frames are screw threaded to the tube, a fuse holder having contact terminals and adapted to be inserted through said passageway into the tube to carry said contact terminals into electrical engagement with the upper and lower contact frames on said tube.

In witness whereof, I hereunto subscribe my name this 2nd day of January A. D. 1909.

EDWARD B. ELLICOTT.
